UNITED STATES PATENT OFFICE.

JOHN C. SCHNEIDER, OF WINONA, MINNESOTA.

STEAM-BOILER.

SPECIFICATION forming part of Letters Patent No. 784,894, dated March 14, 1905.

Application filed November 8, 1904. Serial No. 231,920.

To all whom it may concern:

Be it known that I, JOHN C. SCHNEIDER, a citizen of the United States, residing at Winona, in the county of Winona and State of Minnesota, have invented certain new and useful Improvements in Steam-Boilers; and I do hereby declare the following to be a full, clear, and exact description of the invention, such as will enable others skilled in the art to 10 which it appertains to make and use the same:

This invention, which relates to steam-boilers, has for its object the production of a boiler having water-jacketed walls of an improved construction and by which masonry 15 walls are dispensed with and the efficiency of the boiler largely increased.

While my improvement is adapted for employment in connection with steam-boilers generally, I have illustrated and will describe 20 a tubular boiler embodying my invention, although it is to be understood that no limitation is intended by said showing and description.

The nature of the improvements will be readily comprehended, reference being had to 25 the following detailed description and to the accompanying drawings, illustrating the improvements in their preferred form of embodiment, it being understood that various changes and modifications may be made there- 30 in without exceeding the scope of the concluding claims.

In the drawings, Figure 1 is a top plan view of a steam-boiler embodying my invention. Fig. 2 is a vertical longitudinal section of the 35 same, taken on line 2 2 of Fig. 1. Fig. 3 is a front elevation of the same, partly in section. Fig. 4 is a rear elevation of the same, partly in section.

Referring to the drawings by numerals, 1 40 designates the boiler proper, which may be of the usual fire-tube type shown. The side walls 2 3 are each composed of inner and outer walls secured together in separated relation by rivets 4 4 and supported at their lower ends 45 on suitable bases 5 5, of masonry or the like. Each of these side walls are longitudinally corrugated, as shown by the dotted lines in Fig. 1, the securing-rivets being disposed at the bases of the corrugation. By reason of

this construction the walls are increased in 50 strength and rigidity, and increased heating-surfaces are thus provided.

At the lower end of each wall is a mud-drum 6, provided at its end with cover-equipped openings by which access to the drum for the 55 purposes of inspection and cleaning is permitted. Toward the upper end of each wall is a steam-drum 7, similarly equipped at its end with inspection and scraping openings. The walls extend above the steam-drum to 60 form the support for transverse beams 8 9, from which beams the boiler proper is suspended through the medium of bolts 10 10. Preferably each beam is composed of two channels, between which extend the bolts, and 65 11 is a plate resting on the upper ends of the channels and through which the bolts pass. Nuts on the bolts tightened against the plate serve to directly support the boiler proper, and, if desired, these bolts may be supple- 70 mented by other supporting means, not necessarily here shown or described.

An improved feature of my invention resides in the provision of water-jacketed side walls equipped with an upper steam-drum and 75 a lower mud-drum, which drums are accessible for the purposes stated. Another and equally important feature of the invention consists in providing side walls of the construction shown and described which are interchangeable. The 80 inner wall or sheet of each side wall is by reason of the internal heat of the furnace subjected to the greatest wear, and by changing the side walls from right to left, or vice versa, the inner walls which have received the greater 85 wear are brought outwardly and the life of the walls, and consequently of the entire boiler, is greatly prolonged.

The side walls intercommunicate with the boiler proper through the medium of pipes 90 12 and 13 and a pipe 14, which enters a cross connection 15 between the mud-drums at the rear ends thereof. Likewise, also, the extreme upper ends of the side walls are brought into communication with the boiler proper through 95 transverse pipes 16 17, which connect with a vertical pipe 18, leading from the top of the boiler near the front end of the latter. By

the provision of these connections a proper circulation of water is obtained to prevent undue heating and steaming in the side walls and steam-drums, and the efficiency of the boiler 5 is thereby very largely increased.

I claim as my invention—

1. In a steam-boiler, the combination with the boiler proper, of water-jacketed side walls therefor communicating with the boiler 10 proper and having at their lower end mud-drums and at or near their upper end steam-drums, substantially as and for the purpose set forth.
2. In a steam-boiler, the combination with 15 the boiler proper, of water-jacketed side walls therefor, each composed of two corrugated sheets and communicating with the boiler proper and having at their lower end mud-drums and at or near their upper end steam-

drums, substantially as and for the purpose 20 set forth.

3. In a steam-boiler, the combination with the boiler proper, of water-jacketed side walls in communication with the boiler proper, and having upper steam-drums and lower mud- 25 drums, said drums being provided with end openings and closures for said openings.

4. In a steam-boiler, the combination with the boiler proper, of interchangeable water-jacketed walls each having an upper steam- 30 drum and a lower mud-drum.

In testimony whereof I affix my signature in presence of two witnesses.

JOHN C. SCHNEIDER.
